DESIGN FOR A BAND FOR A WRIST WATCH OR SIMILAR ARTICLE

Allan Adler, Burbank, Calif.

Application October 23, 1944, Serial No. 115,935

Term of patent 14 years

(Cl. D45—4)

To all whom it may concern:

Be it known that I, Allan Adler, a citizen of the United States, residing in the city of Burbank, in the county of Los Angeles and State of California, have invented a new, original, and ornamental Design for a Band for a Wrist Watch or Similar Article, of which the following is a specification, reference being had to the accompanying drawing, forming part thereof.

Fig. 1 is a perspective view of a band for a wrist watch or similar article, showing my new design, on an enlarged scale.

Fig. 2 is a plan view of the band of Fig. 1.

I claim:

The ornamental design for a band for a wrist watch or similar article, as shown.

ALLAN ADLER.
